United States Patent Office

Des. 216,367
Patented Dec. 23, 1969

216,367

WALL CABINET

William J. Jasinski, Chicago, Ill., assignor to Republic Molding Corporation, Niles, Ill., a corporation of Illinois

Filed Jan. 9, 1969, Ser. No. 15,263

Term of patent 14 years

Int. Cl. D6—01

U.S. Cl. D33—19

FIG. 1

FIG. 2

FIG. 3

FIG. 4

FIG. 5

FIG. 6

FIG. 7

FIG. 8

FIG. 9

FIG. 10

FIG. 1 is a perspective view of the wall cabinet with the shelves thereof closed;

FIG. 2 is a perspective view of the wall cabinet thereof with the shelves open;

FIG. 3 is a top view of the wall cabinet;

FIG. 4 is a front elevational view of the wall cabinet;

FIG. 5 is a side elevational view of the wall cabinet;

FIG. 6 is a perspective view of a modified wall cabinet according to the present invention;

FIG. 7 is a perspective view of the wall cabinet of FIG. 6; with the drawers thereof open;

FIG. 8 is a top view of the wall cabinet of FIG. 6;

FIG. 9 is a front elevational view of the wall cabinet of FIG. 6; and

FIG. 10 is a side elevational view of the wall cabinet of FIG. 6.

I claim:

An ornamental design for a wall cabinet, substantially as shown and described.
